ASH TRAY

Harold M. Foddy, Colrain, Mass.

Application June 22, 1942, Serial No. 447,892

4 Claims. (Cl. 131—240)

1

This invention relates to ash trays and more particularly to a novel supporting means for lighted cigars or cigarettes, and having a novel relationship with the ash receiving portion of the tray.

Cigarette smokers frequently desire to lay their cigarettes aside temporarily, for longer or shorter periods. It is customary to provide one or more seats or rests around the rim of the ash receiver for this purpose, or where no rests are provided to lean the cigarette on the rim of the tray with the lighted end resting on the bottom of the tray.

Both of these methods have been recognized as unsatisfactory because where there is a substantial surface contact between the burning portion of the cigarette and the tray for any substantial length of time incomplete combustion occurs, resulting in the production of tar-like substances which not only stain the paper of the cigarette but also destroy the original flavor of the tobacco and impart an acrid taste to the smoke when the cigarette is again picked up and smoking resumed. The sweating of the cigarette and the production of the tar-like deposits also foul the supports. Numerous attempts have been made to overcome these difficulties by providing supports making a minimum contact with the cigarette, but any contact causes incomplete combustion, uneven burning, sweating, and creation of the tarry deposit at the point of contact.

It is the principal object of my invention to overcome these difficulties to a greater extent than hitherto, and in general I accomplish this object by a combination of supporting parts or edges so arranged that the burning cigarette though unattended periodically rearranges itself on the support, prior to objectionable contact of the progressively burning end with the support.

Other and further objects residing in the details of the relative arrangement of the supporting elements by which motion is imparted to the cigarette will be made apparent in the following specification and claims.

In the accompanying drawing the invention is illustrated as applied to a tray formed of plastic or ceramic material but it will be understood that the invention may be applied to supports formed of any material capable of being formed to provide the desired combination of supporting contacts.

Fig. 1 is a plan view of a tray embodying the invention;

Fig. 2 is a fragmentary section substantially on line 2—2 of Fig. 1;

Fig. 3 is a further section substantially on line 2—2 of Fig. 1;

Figs. 4 to 7, inclusive, are diagrammatic plan views of one of the support units, respectively showing positions A, B, C, and D of the cigarette, the cigarette being shown in dotted lines; and

2

Figs. 8 to 11, inclusive, are diagrammatic elevational views of one of the support units looking radially outwardly from the dome and showing the supporting points corresponding respectively to the positions of Figs. 4 to 7, inclusive, the cigarette being omitted.

Referring to the drawings, the tray is shown as comprising a main body 10 having an annular portion 11 upon which the cigarette supports are formed. Inwardly of portion 11 is an ash receiving trough 12 and a central dome-shaped member 14. The body 10 may be secured to a shallow tray 15 of greater diameter than the body 10 and forming an annular receiving trough 16 outwardly of the annular portion 11.

In the illustrative embodiment shown, an annular part of the upper face of portion 11 is formed with a series of support units, two of which are generally indicated at X and Y Fig. 1, spaced around the tray as desired, the number of units employed being a matter of choice. Each unit is formed by shaping the material to provide in each unit sinuous inner and outer edges 17 and 18 separated by depressions 19. In the form illustrated, as is apparent from Fig. 1, the inner edge 17 in one unit crosses over and becomes the outer edge 18 of the next unit. This continuity of edges 17 and 18 between adjacent units is for the purpose of appearance only. Edge 18 in each unit includes the throat 20 of an inclined half cylindrical groove 21 which closely conforms to the diameter of a cigarette.

In the drawing I have illustrated four positions of the cigarette designated A, B, C, and D. A cigarette initially properly placed approximately in position A will successively assume the positions B, C, and D if left unattended. All of the positions are shown in Fig. 1 but are shown separately in Figs. 4 to 7, inclusive.

As best shown in Fig. 2, the dome member 14 is formed with a series of concentric circular channels 22 having sharp edges 23. In initial position A, the cigarette finds a temporarily stable rest with its lighted end resting at point a¹ on the dome and with portions rearwardly of its center resting on a point a² on edge 18 and a point a³ on a downwardly curving edge 25 connecting edge 18 with the edge of groove 21. The elevation of points a¹, a², and a³ are such that the cigarette in position A overlies, without touching, the downwardly curving edge 17 as best shown in Fig. 2. The channel 22 permits a circulation of air to the end of the cigarette until the latter burns to the edge 23 (see a¹, Fig. 2). When the end of the cigarette is thus released from support at the point a¹, that end of the cigarette moves downwardly under the action of gravity and the cigarette engages the inclined edge 17 approximately at the point 17' in Fig. 8. At the point 17' the edge 17 presents a substantially

smooth downward slope and under the action of gravity the forward part of the cigarette moves down this slope and in doing so twists or turns the cigarette to the left, as viewed in Figs. 1 and 4, out of contact with the dome, and to a position of rest at the position B where the cigarette finds a balanced support forwardly on points b^1 and b^2 on edge 17 and rearwardly on point b^3 on edges 18 and point b^4 on edge 25 (see Figs. 1 and 5). It will be noted (see Figs. 3 and 9) that points b^1 and b^2 are at the same elevation on an accurate seat at the convergence of the downwardly converging portions of edge 17, and, as best shown in Fig. 5, that a line drawn through points b^1 and b^2 is at substantially right angles to the longitudinal axis of the cigarette when in position B, so that the support afforded by points b^1 and b^2 is relatively stable, and not a potential source of movement. The rearward points of support b^3 and b^4 are at a slightly higher elevation than points b^1 and b^2 (see Fig. 9) so that the cigarette rests in a slightly downwardly inclined position as best shown in Fig. 2. Point b^3 is on a downwardly inclined portion of edge 18 and point b^4 is on downwardly inclined edge 25, slightly higher than the previously mentioned point b^3 . It will also be noted from Figs. 1, 5, and 9 that the edge 25, on which point b^4 is located, slopes rearwardly and toward the longitudinal axis of the cigarette while the portion of edge 18 on which point b^3 is located slopes forwardly and toward said longitudinal axis. The points b^3 and b^4 are thus positioned on edges inclined in a direction to impose a counter-clockwise turning force to the cigarette when the weight imposed on either point is substantially increased by the shift of the center of weight of the cigarette, as the latter burns toward the rear. Furthermore, a line T, see Fig. 5, drawn through the points b^3 and b^4 makes an angle V, which is other than a right angle, with the line S which is drawn between the centers of the seat b^1-b^2 and the seat b^3-b^4 . The line S coincides with the axis of the cigarette when the latter is in position B. As long as the major portion of the weight of the cigarette is on the seat b^1-b^2 the cigarette retains its position B. Due to the fact that the line T crosses the axis of the cigarette at other than a right angle the points b^3-b^4 are potentially capable of exerting a counter-clockwise torque on the cigarette, tending to turn the cigarette into a position along a line R at right angles to the line T between the points b^3 and b^4 . This torque becomes effective as the cigarette burns back, the relative pressure on points b^1 and b^2 decreasing as the center of gravity shifts toward the mouth end of the cigarette while the pressure on the torque points b^3 and b^4 increases. As the pressure on the torque points b^3 and b^4 increases the cigarette tends to turn counter-clockwise, as indicated by the arrow in Fig. 5, to bring its longitudinal axis at right angles to the line through points b^3 and b^4 . The effectiveness of the torque is increased by the fact that points b^3 and b^4 as above pointed out are on edges having a steep downward pitch whereas the curvature between points b^1 and b^2 is relatively slight as best shown in Fig. 9 and also shown in Fig. 3 in unit Y.

In its turning movement from position B the rear end of the cigarette tips downwardly as it turns while the burning end rises until at the completion of the movement the cigarette comes to rest in a substantially horizontal position C, best shown in Fig. 6. In position C the axis of the cigarette lies in the vertical plane passing

through the axis G of the groove 21 and the mouth end portion of the cigarette is supported at points c^1 and c^2 on the throat 20 of groove 21. The burning end portion of the cigarette rests on a point c^3 on edge 17, the point c^3 being approximately on the line R of Fig. 5. As shown in Fig. 10 the points c^1 , c^2 and c^3 are at approximately the same elevation. The movement from position B to position C will be gradual or abrupt depending on the steepness of the curvature of the supporting edges employed. The cigarette will remain in position C until it burns back to the point of overbalance when the lighted end is tipped up in a substantially vertical plane to the position D where the rear portion is seated snugly in groove 21. The cigarette will then continue to burn, but at a diminished rate because of its upwardly tilted position, until the throat 20 is reached, at which point it is extinguished by the close confinement of the walls of the groove.

For reasons of clearness of illustration the several positions have been shown quite widely separated and the movements described as relatively abrupt. It will be understood, however, that a greater or less number of successive movements may be provided and such movements may be made abrupt or gradual by suitably varying the angle or abruptness of the slopes involved. In the illustrative embodiment, the first movement, from position A to B, is broadly effected by the interposition of a sloping edge 17 slightly below and between initial "end" supports, the sloping edge serving to direct the cigarette to a new position of rest when one of the initial supports is released by the burning of the cigarette. The described movement from B to C is broadly effected by the shifting of the pressure to the points b^3 and b^4 as the cigarette is further consumed. This pressure acts by virtue of the torque resulting from the inclination of the edges on which either one, or both, of the points b^3 and b^4 are located and also by the torque imposed by the position of these points relative to the longitudinal axis of the cigarette. It is not essential that these several torque producing arrangements be combined as shown, the use of any one will serve my purposes.

The order of the positions is not essential nor is the invention limited to any particular number of movements. For some purposes the provision of a single sidewise movement to or from a horizontal or inclined position or between inclined positions may be all that is desired. By my invention it is possible by any of the several means described above to cause the cigarette to adjust itself to a new position one or more times to maintain the lighted end in a position for free burning and to minimize sweating and the formation of objectionable deposits, and the illustrative embodiment described will enable those skilled in the art to apply my novel method in various ways in the control of an unattended cigarette.

While in the preceding description I have referred to designated "points" of contact, these points are not critical since cigarettes are seldom perfectly round and the cigarette in practice has a substantial latitude in finding its several positions of rest on the supports.

What I claim is:

- An ash tray which comprises an elevated rim portion and an ash receiving trough formed inwardly thereof, said rim portion having sharply defined inner and outer edges, the surface of said rim between the edges being depressed, a seat for supporting the mouth end of a cigarette

formed on said outer edge, a second seat for supporting the burning end of a cigarette formed on said inner edge, the second seat being at a lower elevation than the first seat, a line through the first seat making an angle of less than a right angle with a line drawn between the centers of the seats, said inner edge adjacent said second seat sloping upwardly to approximately the level of the first seat at a point on a line at right angles to said line through the first seat.

2. An ash tray which comprises an elevated rim portion and an ash receiving trough formed inwardly thereof, said rim portion having sharply defined inner and outer edges, the surface of said rim between said edges being depressed, said outer edge including downwardly converging portions providing points of support forming a seat for the mouth portion of a cigarette, said inner edge including downwardly converging portions providing points of support forming a seat for the burning portion of the cigarette, said second seat being at a lower elevation than said first seat, the points forming said first seat lying on a line making an angle less than a right angle with a line connecting the centers of said seats to impose a torque tending to twist the cigarette from the second seat when a major portion of the weight of the cigarette is imposed on the first seat, the downwardly converging portion of the inner edge adjacent said second seat forming a guide for directing the burning portion of the cigarette upwardly to a point of rest on said inner edge on a line substantially at right angles to the line through the points forming said first seat.

3. An ash tray which comprises a member having an annular elevated rim portion and an ash receiving trough formed inwardly thereof, a portion extending outwardly from the rim and formed with an outwardly and downwardly inclined groove having sharply defined edges, the upper surface of the rim portion having sharply defined inner and outer edges, the surface of the rim between said edges being depressed, said outer edge including portions converging downwardly to the inner end of said groove, said inner edge including portions converging downwardly to a seat for the burning end portion of a cigarette, said seat being positioned at a lower elevation than the adjacent end of said groove, one edge of said groove and the opposite downwardly inclined portion of the outer edge providing points of support forming a seat for the mouth end portion of the cigarette, a line passing through the points forming the last-named seat making an angle less than a right angle with a line connecting the centers of the seats to impose a torque tending to twist the cigarette from the first-mentioned seat when a major portion of the weight of the cigarette is imposed on the points forming the seat at the mouth end portion of the cigarette, one of the downwardly converging portions of said inner edge adjacent the first seat forming a guide for directing the burning end portion of the cigarette upwardly to a position of rest on said inner edge on a line in the vertical plane of the axis of said groove.

4. An ash tray which comprises a member having an annular elevated rim portion and a central dome portion with an annular ash receiving trough between the rim and dome, a portion extending outwardly from the rim portion and formed with an outwardly and downwardly inclined groove having sharply defined inner and outer edges, the surface of the rim between said edges being depressed, said outer edge including portions converging downwardly to the inner end of said groove, said inner edge including portions converging downwardly to a seat for the burning end portion of a cigarette, said seat being positioned at a lower elevation than the adjacent end of the groove, the inner end of the groove and said dome providing means for supporting a cigarette in bridging relation to one of said downwardly converging portions of said inner edge at one side of said seat, said bridged edge forming a guide to direct the burning end portion of the cigarette into said seat when released from the dome, one edge of said groove and the opposite downwardly inclined portion of the outer edge providing points of support forming a seat for the mouth end portion of the cigarette when the burning end portion is seated in said first seat, a line passing through the points forming the second seat making an angle less than a right angle with a line connecting the centers of the seats to impose a torque tending to twist the cigarette from the first seat when a major portion of the weight of the cigarette is imposed on the points forming the seat at the mouth end portion of the cigarette, the other of said downwardly converging portions of said inner edge adjacent the first seat forming a guide for directing the burning end portion of the cigarette upwardly to a position of rest on said inner edge on a line in the vertical plane of the axis of said groove.
